Application May 28, 1934, Serial No. 727,971

12 Claims. (Cl. 207—10)

This invention relates to the formation of slugs from relatively soft metals and the like and the extrusion of the slugs into tubular members. It has particular reference to the formation of slugs 5 for and the production of collapsible tubes from tin, lead, aluminum, or soft alloys of various metals or similar extrudable materials.

Heretofore it has been the common practice in the production of collapsible tubes to form 10 them by a casting process or by stamping from a flat sheet. Cast slugs are extremely difficult to make uniform and without surface defects which are apt to produce cracks or other imperfections in the walls of extruded tubes. Furthermore, the grain of the metal in a cast slug does 15 not seem to be productive of the best results when extruded. Slugs stamped from rolled, flat sheets are more satisfactory but are expensive due to the production of a relatively large amount of 20 scrap in the course of stamping.

According to the present invention slugs are formed from rolled or drawn stock without the production of scrap. In this way the combined 25 advantages of the prior practices are obtained without the disadvantages of either. The slugs are produced inexpensively, without surface defects and with the grain of the metal arranged for best results in the extrusion operation.

More particularly the invention involves the 30 production of slugs from a continuous strip of wire, preferably round; although wire of any other convenient form of cross-section may be employed. The wire is severed into sections of appropriate length to form individual slugs and 35 the sections are then pressed into slugs of desired thickness. These slugs need not be made truly circular nor of any specific, regular contour, although if the machine for producing the slugs is properly adjusted, a circular slug may be readily formed. It will be found that, upon extrusion, 40 tubes without imperfections and having uniform wall thicknesses will be produced even when slugs of irregular contour are used. The only effect of the irregularity of the slugs is to provide a slightly 45 more irregular free edge at the upper end of the tube than is produced by a strictly circular slug but this is not seriously objectionable due to the common practice of trimming a substantial portion from the end of the tube in finishing it 50 for the market.

Other features and advantages of the invention will appear from the detailed description of certain 55 illustrative examples which will now be given in conjunction with the accompanying drawings, in which:

Fig. 1 is a rear elevation of a machine embodying or adapted to carry out the invention.

Fig. 2 is a vertical section taken along the line 2—2 of Figure 1.

Fig. 3 is a horizontal section along the line 3—3 of Figure 2.

Fig. 4 is a transverse section through the cutting and forming die.

Fig. 5 is a side elevation, on an enlarged scale, 5 of a portion of the machine.

Fig. 6 is a vertical section showing, on an enlarged scale and in greater detail, a portion of the structure illustrated in Figure 2, but with the parts shifted.

Fig. 7 is an enlarged horizontal section similar to Figure 3, showing a modified construction.

Fig. 8 is a vertical section taken along the broken line 8—8 of Figure 7.

Fig. 9 is a horizontal section through a portion 15 of a machine embodying a further modified construction and is taken along the line 9—9 of Figure 10, and

Fig. 10 is a vertical section along the line 20 10—10 of Figure 9.

Referring now to Figures 1 to 6, inclusive, of the drawings, there is illustrated one form of machine capable of forming extrudable slugs in accordance with the present invention. The machine comprises a main frame structure 10 supporting, in a suitable bearing near its top, a shaft 11 adapted to receive power from any convenient source, as by means of a pulley wheel 12, secured to one end of the shaft and connected by a belt to a power line not shown. Adjacent its 30 opposite end the shaft 11 carries a pinion 13 cooperating with a large gear 14 secured to a shaft 15 that may be considered the main drive shaft of the machine. As will be hereinafter explained, all of the operating portions of the machine are 35 driven by suitable connections from this main drive shaft.

At the rear of the machine there is provided an auxiliary standard 16 (Fig. 2) secured in any convenient way to the main frame, or otherwise 40 associated therewith, and arranged to support a shaft 17 adapted to carry a spool or drum 18 having wound thereon a suitable supply of the extrudable metal to be formed into slugs. This metal may conveniently be in the form of a round 45 wire 19 of sufficient diameter to produce a slug of desired size when severed into appropriate unit lengths. If desired the wire may have other forms of cross section, although it is considered simplest to provide and deal with a round wire. 50 Arms 20 secured to the standard 16 extend upwardly at an angle and carry at their outer ends a shaft 21 upon which is slidably and rotatably mounted a grooved guide-wheel or roller 22. The wire as it is drawn from the spool is passed over the grooved guide-wheel, which is arranged to slide from side to side as the point from which the wire is withdrawn from the spool shifts in an axial direction. Any suitable braking means or the 55

like, not shown, may be provided to prevent over-rotation of the spool 18 as the wire is withdrawn, in the manner to be presently explained. Furthermore, if desired, any suitable type of straightening mechanism may be provided to remove the curl from the wire as it leaves the roller 22. After leaving the roller 22, or the straightening device, the wire is fed between a pair of grooved wheels or rollers 23 and 24, which constitute the wire feed means. Roller 23 is carried by a shaft 25 mounted in suitable brackets 26 secured to the main frame of the machine. The roller 24 is carried by a shaft 27 rotatably mounted in the brackets 26. If desired the feed rollers 15 may be arranged to slide along their supporting shafts in a manner similar to the roller 22 but ordinarily this will not be necessary.

For the purpose of rotating the shaft 27, it is provided with a pinion 28 (Fig. 6) adapted to mesh with a gear 29 secured to a shaft 30, also carried by the brackets 26. A ratchet wheel 31 secured to the shaft 30 is engaged by a pawl 32 urged by a spring 33 into engagement with the ratchet. The spring and pawl are suitably mounted upon a frame or yoke 34 pivotally carried by the shaft 30. A pivot pin 35 is adjustably mounted in an opening 36 extending longitudinally of the yoke. To enable adjustment of the pin, it may be mounted upon a screw 37 provided with any suitable means for adjusting it and retaining it in any set position. The pin 35 serves to connect the yoke with a link 38 pivotally connected at its lower end, by means of a pin 39, to the end of an arm 40 secured to a rod or shaft 41. An arm 42 also secured to this shaft carries a roller 43 adapted to engage the periphery of a cam 44 secured to a shaft 45. A spring 46, connected at one end to the arm 40 and at its other end to a suitable point on the frame structure, serves to hold the roller 43 against the cam. As best shown in Figures 1 and 5, the shaft 45 carries a sprocket wheel 47 connected by a chain 48 with a similar sprocket wheel 49 secured to the main drive shaft 15. The construction is such that upon each rotation of the shaft 15, one full revolution will be imparted to the shaft 45.

It will be apparent that as the shaft 45 is rotated clockwise from the position shown in Figure 6, the cam 44 will permit the spring 46 to rock the arms 40 and 42 in a clockwise direction to rock the frame 34 and thereby carry the pawl 32 idly over the teeth of the ratchet wheel 31. Now, after the cam has rotated through approximately 180 degrees from the position shown in Figure 6, the roller 43 will be gradually forced outwardly to rock the arm 40 and the frame 34 counter-clockwise and thus cause the pawl 32 to rotate the shaft 30 through a predetermined angle in a counter-clockwise direction. The extent of rotation of the shaft 30 may be varied by the adjustment of the pin 35 in the manner previously explained. As the shaft 30 is rotated, the shaft 27 and grooved wheel 24 will also be rotated to feed the wire 19 forwardly. A suitable feeding pressure is maintained upon the wire by mounting the supporting shaft 25, for the upper grooved roller 23, in blocks 50 slidable vertically in an opening 51 in the brackets 26. Springs 52 interposed between the tops of the openings 51 and the upper surfaces of the blocks 50 urge the latter downwardly and thus urge the upper roller under a considerable pressure against the wire.

Upon leaving the feed rollers the wire 19 is

passed through a guide sleeve 53 extending through the wall of a die holder 54 and through the wall of a die 55 suitably retained within the die holder. The feeding of the wire is preferably so regulated that upon each rotation of the shaft 45 a section of the wire of predetermined length will be fed across the opening in the die. Preferably this section will extend substantially completely across a diameter of the die opening. If desired, the extent of feeding of the wire upon each cycle of the machine may be governed by the engagement of the end of the wire with the die wall and the feed rollers may then simply slip relative to the wire. It is normally preferred, however, to control the feed by means of the screw 37.

After a section of the wire has been introduced into the die in this manner, it is severed by the cooperation of a punch or plunger 56 with the edge of the die or the end of the sleeve 53. The punch is of substantially the same diameter as the opening in the die so as to form a relatively tight fit with the die opening in its downward travel. For the purpose of reciprocating the punch, it is carried by a vertically slidable head 57 and may be retained in the head by any suitable means, such as the setscrew 58, shown in Figure 2. The head 57 is mounted for vertical reciprocation between a series of guides 59 (Fig. 1). One of a pair of toggle members 60 and 61 is pivotally connected to the head 57 while the other of these members is pivotally connected to a block 62. This block is held fixed during the operation of the machine but may be adjusted vertically to vary the position of the plunger 56 at the two ends of its stroke. For this purpose a wedge 63 is adapted to be forced between a fixed portion of the frame and the block 62, to any extent desired, upon rotation of a hand-wheel 64. To the pivot 65, between the toggle members, there is connected a link or yoke 66 mounted at its opposite end upon an eccentric portion 67 of the shaft 15. Through this connection each rotation of the shaft 15 will cause a straightening and breaking of the toggle and will thus cause reciprocation of the head 57 and the plunger 56. After the plunger has severed the section from the end of the wire 19, it continues its downward movement toward the bottom of the die and squeezes the wire into a flattened slug, as best indicated in Figure 6. It will be apparent that the thickness of this slug may be varied by appropriate adjustment of the hand-wheel 64. If just sufficient metal is provided, the wire may be squeezed until it forms a substantially circular slug completely filling the area of the die. However, as has been previously stated, it is not essential that the slug be made completely circular inasmuch as a slug of somewhat irregular contour may be extruded into a satisfactory tube.

After the slug has been formed, provision must be made for its removal from the die. For this purpose the bottom of the die is preferably formed by an enlarged head 68 at the upper end of a plunger 69 slidable vertically within a guide sleeve 70 passing through the bed of the machine and the die holder. A yoke 71 secured to the lower end of the plunger is pivotally connected to one end of a lever 72 pivoted at 73 upon the frame. The opposite arm of the lever is connected, by means of a yoke 74, with a vertically extending rod or link 75. At its upper end this rod is connected by a yoke 76 to an arm 77 of a bell crank lever, the other arm 78 of which carries a roller 79 cooperating with a cam 80 secured to the shaft 15. A

spring 81 surrounding the rod 75 is confined between a nut 82 secured to the rod and a bracket 83 secured to the frame. Accordingly the spring 81 urges the rod downwardly and the roller 79 into engagement with the cam 80. By means of screw-threaded connections 84 and 85 at the two ends of the rod 75, the precise field of movement of the lever 72, and hence of the plunger 69, may be varied, as desired. This construction is such that 10 at the appropriate point in the cycle of operation of the machine the roller 79 will drop from the high portion of the cam 80 to a low portion and thus permit the spring 81 to rock the lever 72 and lift the plunger 69 and thereby carry a previously formed slug to the upper surface of the die.

When the slug is elevated in the manner explained, it will be engaged by an arm 86 having a V-shaped notch formed adjacent its outer end. This arm is pivoted upon a stud 87 carried by the 20 frame of the machine and is connected intermediate its ends with a rod 88, the opposite end of which is attached to an arm 89. This arm, pivoted at 90 to the main frame, carries a roller 91 at an intermediate point arranged to engage a cam 92 secured to the shaft 45. A spring 93, surrounding the rod 88 and co-acting between a collar 94 secured to this rod and a bracket 95 secured to the frame, urges the rod toward the right, in Fig. 6, and thus holds the roller 91 against the 25 cam 92. As a depression 96 in the cam is brought in line with the roller, the spring 93 urges the rod 88 toward the right (Fig. 6) and thus rocks the arm 86 from the dotted line to the full line position shown in Fig. 3. This occurs after the 30 plunger 69 has been elevated to hold the slug adjacent the top of the die. The movement of the arm 86 may be such as to throw the slug into a chute or into any suitable form of container appropriately placed to receive the slug.

40 The operation of the machine just described should be clearly understood from the detailed description just given. However, the co-ordination of the several parts of the machine will now be briefly set forth. As the shaft 11 is continuously rotated by the belt and pulley drive, or by any other convenient power means, the shafts 15 and 45 will be rotated in synchronous relation. Shaft 45, through the action of cam 44, will rock the frame 34 upon each rotation to turn the 45 ratchet wheel 31 through a predetermined distance in a counter-clockwise direction (Fig. 6). This will rotate the feed roller 24 in a clockwise direction through a corresponding distance. By the action of the upper feed roller 23 bearing 50 downwardly upon the wire, the latter will be fed forwardly to an extent equivalent to the rotation of the roller 24. The forward end of the wire will be passed into the die opening and will extend substantially across the same. Punch or 55 plunger 56 will at this time move downwardly to engage the wire and sever the end which extends beyond the guide sleeve 53. Upon continued downward movement of the plunger, the severed section of wire will be pressed into a flat, substantially circular slug. As the plunger 56 rises, the plunger 69 will also be lifted by the action of cam 80 and spring 81 and the slug will thus be raised to the upper surface of the die. The arm 60 69 will then be operated under the control of the cam 92 to eject the slug from the machine. It will be understood that the various cams for controlling the different portions of the mechanism are so formed as to properly time the movements of the various parts so as to avoid any interference 65 in their operations.

Referring now to Figures 7 and 8, there is illustrated a modified construction in which the severing of small sections from the end of a strip of wire is performed by a separate tool from that employed to flatten the severed section into a slug. 5 In this machine the strip of wire 100 may be fed from a roll, just as in the machine described above, and may be drawn from the roll by means of a pair of grooved feed rollers 101 and 102, similar to the rollers 23 and 24. The mechanism for driving the lower feed roller 102 may comprise a rocking frame 103 carrying a pawl 104 adapted to operate upon a ratchet wheel and drive the roller through suitable gearing, in the manner explained in connection with roller 24. The frame 103 is 10 connected by a link 105 with an arm 106 secured to a shaft 107 which in turn has another arm 108 carrying a roller 109 arranged to engage the periphery of a cam 110. This cam is carried by a shaft 111 which corresponds with the shaft 45 15 of the first machine and may be driven through similar connections from the main drive shaft. A spring 112 connected with the arm 106 and with a portion of the frame serves to hold the roller 109 against the cam. It will be apparent that upon 20 each rotation of the shaft 111, the wire 100 will be advanced a predetermined extent.

The free end of the wire is passed through an opening in a guide block 113 secured to the frame. The receiving end of the opening is preferably 25 flared, as indicated at 114, so as to freely receive the end of the wire. As the strip is fed forward, it is brought into engagement with a stop 115 secured to the block 113. In order to permit adjustment of the stop, it is preferably 30 provided with elongated slots, as shown in Figure 7, cooperating with screws 116. The arrangement is preferably such that the wire 100 is fed, upon each rotation of the shaft 111, just 35 a sufficient distance to carry the end of the wire 40 from a point adjacent the right-hand end of the block 113 (Fig. 8) into engagement with the stop 115. If desired, the feed rollers may be adapted to impart an additional feed movement and the length of the section to be severed may be 45 regulated accurately simply by the adjustment of the stop. When the end of the wire engages the stop, the feed roller 102 may simply be allowed 50 to slip slightly relative to the wire. A vertically reciprocating head 117 (Fig. 10), similar to the head 51, carries a cutter 118 held in position on the head by means of a setscrew 119. As the head descends, upon operation of the toggle mechanism explained in connection with Fig. 2, the cutter cooperates with the end of the block 55 113 to sever the small protruding section from the end of the wire. This section then drops into a trough 120 secured to the end of the block 113.

Means are provided for transferring the severed section from a point below the cutter to 60 the opening in a die 121 carried by a die holder 122. For this purpose a reciprocating rod 123 is provided. This has an extension 124 secured to its top adapted to engage over the upper surface of the severed section lying within the trough 65 120. By this arrangement, as the rod is shifted toward the right (Fig. 8), the severed section is shifted to a point directly over the opening of the die and it is held in a horizontal position by the extension 124 until it is placed squarely over 70 the die opening. The rod 123 is secured to a slide 125 mounted in a suitable passageway provided in the frame. At its left end (Fig. 8) the slide carries a pivotally mounted, square block 126 arranged to cooperate with an elongated 75

opening 127 at the upper end of an arm 128. This arm is pivotally mounted upon a shaft 129 and carries intermediate its ends a roller 130 adapted to engage the periphery of a cam 131. 5 A spring 132, which is connected at one end to the arm 128 and at its opposite end to a portion of the frame, serves to hold the roller against the cam. Upon each revolution of the shaft 111, the slide 125 is reciprocated to transfer the severed section from beneath the cutter to the die opening, in the manner explained.

Cooperating with the die is a plunger 133 mounted in any suitable way upon the reciprocating head 117. The arrangement is such that 15 as the cutter 118 severs a section from the end of the wire, the plunger 133 simultaneously presses and flattens a previously severed section to form a slug. After the slug has been formed it is lifted to the top of the die by means of a 20 plunger 134 operated in the same manner as the plunger 69 of the first embodiment.

As the slug is brought to the top of the die, it may be ejected from the machine by means of 25 a bell-crank 135 pivoted at 136 upon the die holder. This bell-crank has a curved surface 137 adjacent the end of one arm adapted to engage the slug as the bell-crank is oscillated and thus throws the slug into a bucket or other suitable receptacle located nearby. For the purpose of rocking the bell-crank, it is provided with 30 an elongated slot connected with a pin 138 carried by a yoke 139 secured to a rod 140. At its opposite end this rod is connected by a yoke 141 to the upper end of an arm 142 mounted upon 35 the shaft 129. A roller 143 carried by this arm engages the periphery of a cam 144 secured to the shaft 111. A spring 145, surrounding the rod 140 and having one end engaging a collar 146 secured to the rod and its other end engaging 40 a lug 147 extending from the frame, serves to hold the roller 143 against the cam. As the cam rotates, a bump 148 is brought into engagement with the roller and draws the rod 140 toward the left (Fig. 7) against the action of spring 45 145 and thus rocks the bell-crank to throw the slug in the manner explained.

A further modification is illustrated in Figures 50 9 and 10. The machine of this embodiment is in most respects the same as that just described but it is provided with an extrusion punch so that the slug may not only be formed but it may be extruded into a collapsible tube upon the same machine. For this purpose means have been provided for transferring the slug formed in the 55 die 121 of Figure 8 to a die from which the tube may be extruded. A lever 149 is pivoted at 150 upon the die holder and at its outer end is connected with the rod 140 of the construction illustrated in Figure 7. The opposite end of the 60 lever is provided with a curved surface 151 adapted, upon rocking of the lever, to engage the slug and slide it along an arcuate guide surface 152. This surface is curved about the axis of pivot 150 as a center and is carried by a plate having elongated slots 153 cooperating with bolts 154. This slot and bolt construction provides for a slight 65 adjustment of the guide surface so as to accommodate slugs of somewhat different diameters. It will be apparent that as the lever 149 is rocked, the slug will be carried from the die 121 to a 70 stop 155 which may be adjusted, to accommodate slugs of slightly different diameters, by means of screws 156 cooperating with elongated slots in the stop. The stop is so arranged and the stroke 75 of the lever 149 is so regulated that at the end

of the stroke the slug will be positioned directly over the opening in an extrusion die 157. A punch 158, carried by a rockable member 159 on the head 117 and held in place in said member by a setscrew 160, is adapted to extrude the 5 slug into a suitable tube upon the downward movement of the head 117. The member 159 may be mounted upon the head and may be rocked during the reciprocation of the head in the manner explained in my co-pending application Serial Number 650,850 filed January 9, 1933. This enables the discharge of the extruded tube by a suitable air-blast when the punch is tilted into the dotted line position shown in Figure 10. A knockout pin 161 and related 15 mechanism may be provided, as more fully disclosed in my above mentioned pending application.

The machine just described operates in the following manner: As the head 117 rises to a point 20 in which the cutter 118 clears the end of the wire 100, the latter is fed forwardly until its end engages the stop 115. During this time the plunger 133 is withdrawn from its die and the plunger 134 lifts the previously finished slug to the upper 25 surface of the die. The arm 149 then operates to carry this slug against the stop 155 where it drops into the opening in the die 157. As the head 117 reaches the upper limit of its movement, and during the initial portion of its downward 30 movement, the rod 123 is reciprocated to transfer the previously severed section of wire from beneath the cutter 118 to the opening in the die 121. In the meantime the plunger 134 will be returned to the bottom of this die. As the head 117 continues its downward movement, the rod 123 is retracted and the end of the cutter is brought into engagement with the wire to sever another section. Simultaneously, or soon after, the plunger 133 engages the previously severed 40 section that has just been deposited in the die 121 and presses it into a flat slug. At the same time the punch 158 engages the slug, formed on the previous operation and transferred to the die 157, to extrude it into tubular form. The head 45 117 is then again retracted and the same cycle of operations is repeated. It will be understood that the extruded tube is blown or otherwise removed from the punch 158 as the head 117 approaches its upper limit of movement. 50

While several illustrative forms of construction, embodying and capable of carrying out the features of the present invention, have been disclosed in considerable detail, it will be understood that various changes may be made without departing 55 from the general principles and scope of the invention. Features disclosed in connection with one form may be adapted and applied to another of the forms of the invention disclosed.

What I claim is:

1. A method of forming a thin metal tube which comprises severing a section of desired length from a wire formed of extrudable material, depositing said section on its side as distinguished from its end in a die, said section when so deposited filling only a portion of the cross-sectional area of the die, flattening the section within the die to form a slug substantially filling the area of the die, and forcing a punch against the slug to extrude the same. 65

2. A method of forming a thin metal tube which comprises severing a section of desired length from a wire formed of extrudable material, depositing said section on its side as distinguished from its end in a die, flattening the 70 area of the die, and forcing a punch against the slug to extrude the same. 75

section within the die to form a slug, transferring each slug as it is formed to an extrusion die, and forcing a punch against the slug to extrude the same.

5. 3. A method of forming thin metal tubes which comprises intermittently advancing a strip of extrudable material, severing successive sections of uniform length from the end of said strip, transferring the severed sections as they are formed to a die, pressing each section along its side as distinguished from its ends in said die to form a slug, lifting the slug so formed to the top of the die, transferring the slugs successively as they are formed to an extrusion die, and extruding the slugs from said die to form tubes.

10. 4. In a machine for forming slugs to be extruded into thin-walled tubular members, a main operating shaft, means operated by said shaft for advancing a strip of extrudable material a predetermined extent upon each cycle of the machine, said strip being in the form of a wire narrower and thicker than the desired slugs, means for severing a section from the end of said strip upon each cycle of operation, a die for receiving the severed section, means for successively transferring the sections from said severing means to said die, and means for pressing one of said sections in said die to flatten the same upon each cycle of the machine.

15. 5. In a machine for forming slugs to be extruded into thin-walled tubular members, a main operating shaft, means operated by said shaft for advancing a strip of extrudable material a predetermined extent upon each cycle of the machine, said strip being in the form of a wire narrower and thicker than the desired slugs, means for varying the distance through which said strip is advanced upon each cycle of operation, means for severing a section of variable 20 length from the end of said strip upon each cycle of operation, die means for receiving the severed sections, means for transferring the sections from said severing means to said die means successively as they are formed, and means for pressing 25 one of said sections in said die to flatten the same upon each cycle of the machine.

6. In a machine for forming slugs to be extruded into thin-walled tubular members, a main operating shaft, means operated by said shaft for advancing a strip of extrudable material a predetermined extent upon each cycle of the machine, said strip being in the form of a wire narrower and thicker than the desired slugs, means for severing a section from the end of said strip 30 upon each cycle of operation, an adjustable stop in the path of said strip beyond said severing means for definitely limiting each advance of the strip, the construction and arrangement being such that the severed section drops below said 35 stop, a die for receiving the severed sections, a punch arranged to enter said die upon each cycle of operation to flatten said sections, and means for varying the extent of movement of said punch within said die.

65. 7. In a machine for forming slugs to be extruded into thin-walled tubes, a main operating shaft, means operated by said shaft for advancing a substantially round, wire-like strip of extrudable material a predetermined extent upon each 40 cycle of the machine, means for severing a sec-

tion from the end of said strip upon each cycle of operation, a die for receiving the severed sections by gravity on their sides as distinguished from their ends, means for pressing one of said sections in said die to flatten the same upon each 45 cycle of the machine, means for lifting the flattened sections to the top of the die, and means for ejecting said flattened sections from the machine.

8. In a machine for forming slugs to be extruded into thin-walled tubular members, means for feeding a wire of extrudable material, means for severing sections of predetermined length from the end of said wire, a die arranged to receive said severed sections successively by gravity 50 on their sides as distinguished from their ends, said die having a liftable bottom, means for pressing said sections in said die to flatten the sections into slugs, means for lifting the die bottom to the top of the die, and means for shifting the slugs from said die bottom when it is elevated.

9. In a machine of the class described strip feeding means, a pair of dies each having an opening therein, means for severing a section of predetermined length from the end of said strip 55 and depositing the same in one of said dies, means including a member whose lower end is of substantially the same size and shape as the opening in said die for flattening said section in said die, means for transferring the flattened section to the other of said dies, and means for extruding 60 the section as a tube from said other die.

10. In a machine of the class described strip feeding means, a pair of dies each having an opening therein, means for severing a section of predetermined length from the end of said strip, means for transferring the severed section to one 65 of said dies, means including a member whose lower end is of substantially the same size and shape as the opening in said die for flattening said section in said die, means for transferring the flattened section to the other of said dies, and means for extruding 70 the section as a tube from said other die.

11. In a machine of the class described strip feeding means, a pair of dies each having an opening therein, means for severing a section of predetermined length from the end of said strip and depositing the same in one of said dies, means including a member whose lower end is of substantially the same size and shape as the opening in said die for flattening said section in said die, means for transferring the flattened section to the other of said dies, and means for extruding 75 the section as a tube from said other die, said severing, flattening and extruding means operating simultaneously upon different severed sections.

12. In a machine of the class described strip feeding means, a pair of dies, means for severing a section of predetermined length from the end of said strip and depositing the same in one of said dies, means for flattening said section in said die, means for transferring the flattened section to the other of said dies, means for extruding 80 the section as a tube from said other die, and a common reciprocatory member carrying said severing, flattening and extruding means and simultaneously operating the same.
